US011955742B2

(12) **United States Patent**
Sasame et al.

(10) **Patent No.:** US 11,955,742 B2
(45) **Date of Patent:** *Apr. 9, 2024

(54) **ELECTRICAL CONNECTOR WITH CAVITY BETWEEN TERMINALS**

(71) Applicants: **Amphenol FCI Asia Pte. Ltd.**, Singapore (SG); **Amphenol FCI Connectors Singapore Pte. Ltd.**, Singapore (SG)

(72) Inventors: **Naotaka Sasame**, Saitama (JP); **Motomu Kajiura**, Tokyo (JP); **Masahiko Motoyama**, Kanagawa (JP)

(73) Assignees: **Amphenol FCI Asia Pte. Ltd.**, Singapore (SG); **Amphenol FCI Connectors Singapore Pte. Ltd.**, Singapore (SG)

(*) Notice: Subject to any disclaimer, the term of this patent is extended or adjusted under 35 U.S.C. 154(b) by 0 days.

This patent is subject to a terminal disclaimer.

(21) Appl. No.: **17/942,435**

(22) Filed: **Sep. 12, 2022**

(57) **ABSTRACT**

An electrical connector includes a housing, first and second sets of terminals and a spacer. The housing has a first sidewall, a second sidewall spaced apart from the first sidewall and a cavity between the first and second sidewalls. The first set of terminals is disposed in the cavity adjacent to the first sidewall. The second set of terminals is disposed in the cavity adjacent to the second sidewall. The spacer is disposed in the cavity between the first and second sets of terminals.

ELECTRICAL CONNECTOR WITH CAVITY BETWEEN TERMINALS

RELATED APPLICATIONS

This application is a continuation of U.S. application Ser. No. 17/085,342, filed Oct. 30, 2020, now U.S. Pat. No. 11,444,397, issued Sep. 13, 2022, entitled “ELECTRICAL CONNECTOR WITH CAVITY BETWEEN TERMINALS,” which is a continuation of U.S. application Ser. No. 16/745,995, filed Jan. 17, 2020, now U.S. Pat. No. 10,840,622, issued Nov. 17, 2020, entitled “ELECTRICAL CONNECTOR WITH CAVITY BETWEEN TERMINALS,” which is a continuation of U.S. application Ser. No. 15/742,244, filed Jan. 5, 2018, now U.S. Pat. No. 10,541,482, issued Jan. 21, 2020, entitled “ELECTRICAL CONNECTOR WITH CAVITY BETWEEN TERMINALS,” which is a 35 U.S.C. § 371 National Phase filing of International Application No. PCT/SG2016/050317, filed on Jul. 7, 2016, entitled “ELECTRICAL CONNECTOR,” which claims the benefit of and priority to Singapore Patent Application Serial No. 10201505358 W, filed on Jul. 7, 2015, entitled “ELECTRICAL CONNECTOR.” The entire contents of these applications are incorporated herein by reference in their entirety.

FIELD OF THE INVENTION

The present invention relates to an electrical connector, and more particularly relates to an electrical board connector.

BACKGROUND

Electrical connectors are widely used in electrical systems for data communication, data storage, data transmission and the like. Board connectors have been used to establish electrical connections between printed circuit boards (PCBs) to which plug connector and counterpart receptacle connector are mounted respectively.

SUMMARY

According to an embodiment, an electrical connector includes a housing, first and second sets of terminals and a spacer. The housing has a first sidewall, a second sidewall spaced apart from the first sidewall and a cavity between the first and second sidewalls. The first set of terminals is disposed in the cavity adjacent to the first sidewall. The second set of terminals is disposed in the cavity adjacent to the second sidewall. The spacer is disposed in the cavity between the first and second sets of terminals.

Other aspects and advantages of the present invention will become apparent from the following detailed description, illustrating by way of example the inventive concept of the present invention.

BRIEF DESCRIPTION OF THE DRAWINGS

Embodiments of the invention are disclosed hereinafter with reference to the drawings, in which:

FIG. 1 is a perspective view of an electrical connector in accordance with one embodiment of the present invention;

FIG. 2 is a perspective view of a counterpart connector for connecting to the board connector shown in FIG. 1;

FIG. 3 is a front view of FIG. 1;

FIG. 4 is a top view of FIG. 1;

FIG. 5 is an exploded perspective view of the electrical connector shown in FIG. 1;

FIG. 6 is a perspective top view showing the spacer of the electrical connector of FIG. 1;

FIG. 7 is a perspective bottom view showing the spacer of FIG. 6;

FIG. 8 is a perspective view showing the first set of terminals of the electrical connector of FIG. 1;

FIG. 9 is a perspective view of the first set of terminals of FIG. 8 from another viewing angle;

FIG. 10 is a cross sectional perspective view of the electrical connector shown in FIG. 3 along A-A;

FIG. 11 cross sectional perspective view of the electrical connector shown in FIG. 3 along B-B;

FIG. 12 is a perspective view of showing the first and second sets of terminals of the electrical connector shown in FIG. 10;

FIG. 13 is a perspective view of showing the housing of the electrical connector shown in FIG. 10;

FIG. 21 is a perspective view of an electrical connector in accordance with another embodiment of the present invention;

FIG. 22 is a front view of FIG. 21;

FIG. 23 is an exploded perspective view of the electrical connector shown in FIG. 21;

FIG. 24 is a cross sectional perspective view of the electrical connector shown in FIG. 22 along F-F;

FIG. 25 is a cross sectional perspective view of the electrical connector shown in FIG. 22 along G-G;

FIG. 26 is a cross sectional perspective view of the electrical connector shown in FIG. 22 along H-H;

DETAILED DESCRIPTION

As shown in FIGS. 1 to 5, an electrical connector 100 includes a housing 110, a first set of terminals 120, a second set of terminals 160 and a spacer 140. Housing 110 has a first sidewall 112 and a second sidewall 116 spaced apart from first sidewall 112, forming a cavity 114 between first and second side-walls 112, 116. First set of terminals 120 is disposed in cavity 114 and adjacent to first sidewall 112. Second set of terminals 160 is disposed in cavity 114 and adjacent to second sidewall 116. Spacer 140 is disposed in cavity 114 between first set of terminals 120 and second set of terminals 160. Housing 110 defines a depth direction 102, a width direction 104 perpendicular to depth direction 102 and a height, direction 106 perpendicular to depth direction 102 and width direction 104.

As shown in FIGS. 1, 3 and 4, first set of terminals 120 includes first signal pairs 123 and first ground terminals 122. Each of the first ground terminals 122 is disposed between adjacent first signal pairs 123. Second set of terminals 160 includes second signal pairs 165 and second ground terminals 166. Each of the second ground terminals 166 is disposed between adjacent second signal pairs 165. Housing

110 has windows 108 formed on first and second sidewalls 112, 116 (only windows 108 on first sidewall 112 are shown), corresponding to the positions of first and second signal pairs 123, 165. Spacer 140 is positioned closer to first and second ground terminals 122, 166 than to the first and second signal pairs 123, 165. Spacer 140 may be in contact with first and second ground terminals 122, 166 or alternatively, spacer 140 is spaced apart from the first and second ground terminals 122, 166 with an air gap. Windows 108 provide air space for first and second ground terminals 122, 166 which contributes to signal integrity performance of electrical connector 100.

Spacer 140 is electrically coupled to first and second ground terminals 122, 166 to serve as a resonant damping component to improve signal integrity of electrical connector 100.

First signal pairs 123 and first ground terminals 122 may be disposed in a first plane. Second signal pairs 165 and second ground terminals 166 may be disposed in a second plane. As shown in FIGS. 6 and 7, Spacer 140 has a base 141. At one side of base 141 there are formed first ridges 142 projecting from base 141 and facing first set of terminals 120. At an opposite side of base 141 there are formed second ridges 146 projecting from base 141 and facing second set of terminals 160. Between adjacent first ridges 142 there is formed a first notch 143. Between adjacent second ridges 146 there is formed a second notch 145. Each of the first ridges 142 is in alignment with one of the first ground terminals 122 with respect to width direction 104 of housing 110. Each of the second ridges 146 is in alignment with one of the second ground terminals 166 with respect to width direction 104 of housing 110. Each of the first ridges 142 is in contact with one of the first ground terminals 122, each of the second ridges 166 is in contact with the one of the second ground terminals 166. Alternatively, each of the first ridges 142 is spaced apart from one of the first ground terminals 122 with an air gap, and each one of the second ridges 146 is spaced apart from one of the second ground terminals 166 with an air gap.

In one embodiment, as shown with further details in FIGS. 6 to 20, electrical connector 100 includes a first frame 130 and a second frame 150. First frame 130 is molded to and supporting first set of terminals 120, to form a first Insert-Molded Leadframe Assembly (IMLA) 120a. Second frame 150 is molded to and supporting second set of terminals 160, to form a first Insert-Molded Leadframe Assembly (IMLA) 160a. First and second IMLAs 120a, 160a have symmetrical structures and dimensions, hence illustrations and references made in the context to one of the IMLAs applies to those made to the other one of the IMLAs, in conduction with FIGS. 8 and 9. First frame 130 is disposed between first sidewall 112 of housing 110 and spacer 140. Second frame 150 is disposed between second sidewall 116 of housing 110 and spacer 140.

As shown in FIGS. 8 and 9, first frame 130 has side columns 137 and first protuberances 133 facing spacer 140 and notches 132 between protuberances 133. Second frame 150 has second columns 153 and second protuberances 155 facing spacer 140, and notches 156 between protuberances 155. Each one of the first ridges 142 of spacer 140 is disposed in one of the first notches 132, each one of the second ridges 146 of spacer 140 is disposed in one of the second notches 156. Each one of the first and second protuberances 133, 155 is received between adjacent first and second ridges 143, 145 of spacer 140, respectively. First columns 137 and first protuberances 133 form a first recess 139 on first IMLA 120a, facing spacer 140. Likewise second

columns 153 and second protuberances 155 form a second recess 151 on second IMLA 160a, facing spacer 140. The segment of first set of terminals 120 within first recess 139 are dented with respect to first columns 137 and first protuberances 133, and the segment of second set of terminals 160 within second recess 151 are dented with respect to second columns 153 and second protuberances 155. As such, there is formed an air gap between the first set of terminals 120 and spacer 140, and an air gap between the second set of terminals 160 and spacer 140. The air gaps serve to improve signal integrity performance between the signal contacts and spacer 140.

First frame 130 has first ribs 131 facing first sidewall 112 of housing 110. Second frame 150 has second ribs 157 facing second sidewall 116 of housing 110. First ribs 131 separate first set of terminals 120 from first sidewall 112 of housing 110. Second ribs 157 separate second set of terminals 160 from second sidewall 116 of housing 110.

Between first ribs 131 there are formed first openings 1302 through which first set of terminals 120 are partially exposed. Between second ribs 157 there are formed second openings 1508 through which second set of terminals 160 are partially exposed.

As shown in FIGS. 10 to 15, first set of terminals 120 is positioned with a distance 120d from first sidewall 112 of housing 110. Second set of terminals 160 is positioned with a distance 160d from second sidewall 116 of housing 110. First and second openings 1302, 1508 are formed for insert molding process of producing IMPAs 120a, 160a.

FIGS. 14 and 15 shows the positional relationship between spacer 140 and second ground terminals 166, and that between spacer 140 and second signal pairs 165. The positional relationship between spacer 140 and first ground terminals and first signal pairs is the same. As shown in FIGS. 14 and 15, a distance between second ridge 146 of spacer 140 and a second ground terminal 166 is denoted as distance 146d. A distance between second notch 145 and a second signal pair 165 is denoted as distance 145d, in which, distance 145d is greater than distance 146d. Another words, spacer 140 is positioned closer to first and second ground terminals 122, 166 of first and second set of terminals 120, 160 to effect electrical coupling between spacer 140 and first and second ground terminals 122, 166 and achieve signal integrity improvement.

As shown in FIGS. 16 and 17A and 17B, electrical connector 100 includes a pair of fixing tabs 180 secured to housing 110 and engaged to spacer 140. Each of the first and second frames 130, 150 has a pair of grooves 138, 158 into which each one of the fixing tabs 180 is fitted. Each fixing tab 180 has barbs 186 biting into sidewalls 112, 116 of housing 110 such that fixing tabs 180 are securely fixed to housing 110. Each fixing tab 180 has a main body 181 and first and second bosses 182, 186 raised from main body 181. Main body 181 is received into grooves 138, 158 with first and second bosses 182, 186 forced into respective first and second frames 130, 150 in the first and second grooves 138, 158. Each fixing tab 180 has a middle portion 184 engaged to spacer 140 to fix spacer 140 to housing 110.

As shown in FIGS. 18 to 20, connected to first and second sidewalls 112, 116 of housing 110 there is a partition 117 onto which spacer 140 is seated. Partition 117 has one or more recesses 118 formed thereon and accessible through cavity 114. Spacer 140 may include one or more pins 148 projecting downward from bottom surface thereof. Each pin 148 is received into a recess 118 such that movement of spacer 140 relative to housing 110 along depth direction 102 and width direction 104 is prevented.

In another embodiment, as shown in FIGS. 21 to 26, an electrical connector 200 includes a housing 210, first and second sets of terminals 220, 260, and a spacer 240. Housing 210 has a first sidewall 212 and a second sidewall 216 spaced apart from first sidewall 212, and a cavity 214 between first and second sidewalls 212, 216. First set of terminals 220 is disposed in cavity 214 adjacent to first sidewall 212, and second set of terminals 260 is disposed in cavity 214 adjacent to second sidewall 216. Spacer 240 is disposed in cavity 214 between first and second set of terminals 220, 260.

Electrical connector 200 is of a low-profile structure having a relatively smaller height dimension compared to that of the previous embodiment. First and second set of terminals 220, 260 are respectively attached to first and second sidewalls 212, 216 without additional support of a frame. First and second signal pairs 223, 265 are positioned in a relatively greater distance from spacer 240 and spacer 240 is electrically coupled to first and second ground terminals 222, 266 by being positioned closer to such ground terminals, via ridges 242, 246 projecting from spacer 240.

Similar to the previous embodiment, electrical connector 200 includes a pair of fixing tabs 280 fixed to housing 210 to secure spacer 240 to housing to ensure the correct positional relationship with first and second set of terminals 220, 260.

Although embodiments of the present invention have been illustrated in conjunction with the accompanying drawings and described in the foregoing detailed description, it should be appreciated that the present invention is not limited to the embodiments disclosed. Therefore, the present invention should be understood to be capable of numerous rearrangements, modifications, alternatives and substitutions without departing from the spirit of the invention as set forth and recited by the following claims.

The invention claimed is:

1. An electrical connector, comprising:
a housing having a first sidewall and a second sidewall spaced apart from the first sidewall in a first direction; a first set of terminals disposed adjacent to the first sidewall and comprising first signal pairs and first ground terminals, each first ground terminal disposed between adjacent pairs of the first signal pairs, and each of the first set of terminals comprises a mating end, a contact tail, and an intermediate portion coupling the mating end to the contact tail;
a second set of terminals disposed adjacent to the second sidewall and comprising second signal pairs and second ground terminals, each second ground terminal disposed between adjacent pairs of the second signal pairs, and each of the second set of terminals comprises a mating end, a contact tail, and an intermediate portion coupling the mating end to the contact tail; and
a component electrically coupled to the first ground terminals to dampen resonance in the electrical connector, wherein the component comprises first portions protruding toward respective ones of the first ground terminals and first notches disposed between adjacent ones of the first portions.
2. The electrical connector of claim 1, wherein:
the intermediate portion of each of the first set of terminals is elongated from the mating end to the contact tail in a second direction parallel to the first sidewall; the intermediate portion of each of the second set of terminals is elongated from the mating end to the contact tail in the second direction; and

the contact tails of each of the first and second sets of terminals are configured for mounting to a surface that is normal to the second direction.

3. The electrical connector of claim 1, wherein the component is at least partially disposed between the first set of terminals and the second set of terminals.

4. The electrical connector of claim 1, wherein the housing comprises a first frame molded around the first set of terminals and disposed adjacent to the first sidewall and a second frame molded around the second set of terminals and disposed adjacent to the second sidewall.

5. The electrical connector of claim 1, wherein:
the housing comprises a first frame that supports the first set of terminals and comprises second notches; and the first portions of the component are received in respective ones of the second notches.

6. The electrical connector of claim 1, wherein the component is further electrically coupled to the second ground terminals to dampen resonance in the electrical connector.

7. The electrical connector of claim 6, wherein the component comprises:

first portions protruding toward respective ones of the first ground terminals and first notches disposed between adjacent ones of the first portions; and
second portions protruding toward respective ones of the second ground terminals and second notches disposed between adjacent ones of the second portions.

8. A surface-mount electrical connector comprising:
a housing having a first sidewall and a second sidewall spaced apart from the first sidewall in a first direction, and a cavity between the first and second sidewalls; a first set of terminals disposed in a first plurality of slots in the housing adjacent to the first sidewall and comprising first signal pairs and first ground terminals; a second set of terminals disposed in a second plurality of slots in the housing adjacent to the second sidewall and comprising second signal pairs and second ground terminals; and
a component disposed in the housing and electrically coupled to the first ground terminals to dampen resonance in the surface-mount electrical connector, wherein:

the cavity extends through the housing from a first end, adjacent a first surface of the housing, to a second end, adjacent a second surface of the housing that is opposite the first surface; and
contact tails of the first and second sets of terminals are exposed at the first surface and configured for mounting to a surface of a substrate that is parallel to the first surface.

9. The surface-mount electrical connector of claim 8, wherein each of the first set of terminals comprises a mating end exposed at the second surface, one of the contact tails exposed at the first surface, and an intermediate portion elongated from the mating end to the one of the contact tails.

10. The surface-mount electrical connector of claim 8, wherein the component is at least partially disposed between the first set of terminals and the second set of terminals.

11. The surface-mount electrical connector of claim 8, wherein the housing comprises a first frame molded around the first set of terminals and disposed adjacent to the first sidewall and a second frame molded around the second set of terminals and disposed adjacent to the second sidewall.

12. The surface-mount electrical connector of claim 8, wherein the component comprises first portions protruding toward respective ones of the first ground terminals and first notches disposed between adjacent ones of the first portions.

13. The surface-mount electrical connector of claim 12, wherein:
 the housing comprises a first frame that supports the first set of terminals and comprises second notches; and the first portions of the component are received in respective ones of the second notches. 5
14. The surface-mount electrical connector of claim 8, wherein the component is further electrically coupled to the second ground terminals to dampen resonance in the surface-mount electrical connector. 10
15. The surface-mount electrical connector of claim 14, wherein the component comprises:
 first portions protruding toward respective ones of the first ground terminals and first notches disposed between adjacent ones of the first portions; and second portions protruding toward respective ones of the second ground terminals and second notches disposed between adjacent ones of the second portions. 15
16. A board connector assembly comprising:
 a printed circuit board having a surface; and a surface-mount board connector, comprising:
 a housing having a first sidewall and a second sidewall spaced apart from the first sidewall in a first direction, and a cavity between the first and second sidewalls; 20
 a first set of terminals disposed in a first plurality of slots in the housing adjacent to the first sidewall and comprising first signal pairs and first ground terminals, each of the first set of terminals comprising a mating end and a contact tail; 25
 a second set of terminals disposed in a second plurality of slots in the housing adjacent to the second sidewall and comprising second signal pairs and second

- ground terminals, each of the second set of terminals comprising a mating end and a contact tail; and a component disposed in the housing and electrically coupled to the first ground terminals to dampen resonance in the surface-mount board connector, wherein:
 the cavity extends through the housing in a first direction normal to the surface of the printed circuit board from a first end of the housing to a second end of the housing; at the first end, the contact tails of the first and second sets of terminals are mounted to the surface of the printed circuit board; and at the second end, the mating ends of the first and second sets of terminals are exposed. 10
17. The board connector assembly of claim 16, wherein the component is at least partially disposed between the first set of terminals and the second set of terminals. 15
18. The board connector assembly of claim 16, wherein:
 the component comprises first portions protruding toward respective ones of the first ground terminals and first notches disposed between adjacent ones of the first portions;
 the housing comprises a first frame that supports the first set of terminals and comprises second notches; and the first portions of the component are received in respective ones of the second notches. 20
19. The board connector assembly of claim 16, wherein the component is further electrically coupled to the second ground terminals to dampen resonance in the electrical connector. 25
